UNITED STATES PATENT OFFICE.

HIDETARO ICHIHARA, OF PORT BLAKELY, WASHINGTON.

DEVICE FOR APPLYING ADHESIVE MATTER.

1,230,409.

Specification of Letters Patent. Patented June 19, 1917.

Application filed June 6, 1916. Serial No. 102,105.

To all whom it may concern:

Be it known that I, HIDETARO ICHIHARA, a subject of the Emperor of Japan, residing at Port Blakely, in the county of Kitsap and 5 State of Washington, have invented a certain new and useful Improvement in Devices for Applying Adhesive Matter, of which the following is a specification.

My invention relates to improvements in 10 devices for applying adhesive matter in the form of fluid, as paste, to paper or other sheet material that is to be affixed to an object, and the object of my invention is to provide a device which shall embody a container that is adapted to contain a supply 15 of adhesive matter in the form of a fluid with which container shall be associated a rotatable roller so disposed that a portion of its periphery shall be exposed to contact 20 with the contents of said container, whereby the entire periphery of said roller may be coated with the adhesive matter within the container and such matter then be transferred therefrom to a desired surface in response to the operation of causing said 25 surface to move over the roller.

A more particular object of my invention is to provide an operative device which may be disposed in association with a pile of 30 labels and which shall be adapted to operate automatically to apply paste to portions of the back surfaces of said labels in response to the act of removing labels one after another, beginning with the uppermost one, 35 from said pile of labels.

I accomplish these objects by devices illustrated in the accompanying drawings where- 40 in Figure 1 is a plan view of the form of structure embodying my invention; Fig. 2 is a view in side elevation of the same; Fig. 3 is a fragmentary view of the same on a larger scale in vertical section on broken line z, z of Fig. 1; Fig. 4 is a view of parts 45 of the same in vertical section on broken line y, y of Fig. 1; and Fig. 5 is a fragmentary view of the same in vertical section on the same broken line y, y of Fig. 1 showing certain parts in inoperative positions.

Referring to the drawing, throughout 50 which like reference numerals indicate like parts, I have illustrated one form of structure embodying my invention, which form is particularly adapted for use in a cannery in the operation of applying adhesive ma- 55 terial to an end portion of the back surface

of a label that is to be affixed to a cylindri- 60 cally formed can of food products, and such structure includes a base portion 29 upon one end portion of which are mounted two oppositely disposed vertical guiding mem- 65 bers 30 and 31 which serve to guide an inverted container 32 which is disposed therebetween to be slidably movable in vertical directions, said container 32 being of oblong form in cross-section and provided 70 with rods 33 attached one to the outer surface of each of its opposite narrower vertical sides in a line parallel therewith, which rods 33 engage with the guiding members 30 and 31 to guide the container 32 in its vertical movements.

The bottom end wall of the container 32 is provided with an oblong slotted opening 34 therethrough which opening may be closed tightly, at times required, by a cover 75 35 which is hinged to said bottom end wall on a line adjacent to said opening 34.

The cover 35 is provided with a soft pad 80 36 on its engaging side more tightly to close said opening 34, and said cover 35 may be maintained in its closed position, as shown in Fig. 5, by a spring 37 associated therewith.

Pivottally attached to the bottom end of the container 32 on the broader side of it, 85 opposite the cover 35, are two arms 38 that are united by an integral pivot shaft 39, and rotatably mounted on the free ends of said arms 38 to extend therebetween is a roller 40 whose periphery is covered with 90 yielding material 41, as felt or soft vulcanized rubber.

The forms and positions of the arms 38 are such that they may be swung to move the roller 40 from its position shown in Fig. 4 95 to its position shown by broken lines in Fig. 5 when it is desired to close the opening 34 with the cover 35.

The arms 38 are each provided with a spring 42 which tends to maintain the roller 100 40 in the position to cover the opening 34.

To utilize the structure the container 32 is removed from the guiding members 30 and 31 and turned to a position with its slotted opening 34 uppermost and then filled with 105 fluid paste and thereupon the roller 40 is disposed to close said opening 34; then a pile of labels 43, shown in Figs. 2 and 4, is placed on the base 29 with their printed sides down and with their end portions (that 110

are to be supplied with paste) disposed between the two guiding members 31 and 30, as indicated in Fig. 2, whereupon the container 32 is inverted and placed between the 5 guiding members 30 and 31 with the roller 40 disposed to rest on the top of the pile of labels 43, as shown in Fig. 4, whereby, when one label after another is pulled endwise from the top of the pile of labels 43, 10 the roller 40 will rotatively move to deposit paste on said labels successively, said paste being carried by the periphery of the material 41 from the interior of the container 32 to the surface of said labels in an obvious manner.

Manifestly many changes may be made in the forms, dimensions and arrangement of parts of my invention without departing from the spirit thereof.

20 What I claim is:

1. A device of the class described comprising a base, vertical guide-standards carried thereby, an adhesive applying receptacle slidably associated with said standards, 25 the bottom of said receptacle having an opening therein, and a swinging gate closure and swinging adhesive roller interchange-

ably associated with said opening, and exteriorly positioned relative to the receptacle.

2. An adhesive applying device having an exit opening therein, movable means for sealing said opening, and adhesive applying means movable to a position adjacent the opening upon removal of the sealing means, the sealing and adhesive applying means being 35 swingingly mounted on opposite sides of said opening and moving in opposed directions.

3. Means for applying adhesive including base-supported standards, an adhesive receptacle, side lugs carried by the receptacle for sliding engagement with said standards, there being an opening in said receptacle, a tensioned flap-valve adapted to close said opening, and a tensioned roller movable to 45 a position adjacent said opening when the flap-valve is opened, the valve and roller being positioned exteriorly of the receptacle.

In witness whereof, I hereunto subscribe my name this 20th day of May, A. D. 1916. 50

HIDETARO ICHIHARA.

Witnesses:

FRANK WARREN,
O. JOHNSON.
